FIG. 1

FIG. 2

FIG.3

FIG.4

FIG.5

FIG. 6

FIG. 7

FIG. 8

FIG. 9

FIG. 10

FIG. 1 is a top plan view of an electric conductor bar and guard support embodying my new design.

FIG. 2 is a side elevational view of the lower side of the electric conductor bar and guard support shown in FIG. 1, the opposite side being a mirror image thereof.

FIG. 3 is an elevational view of the left-hand side of the electric conductor bar and guard support shown in FIG. 1.

FIG. 4 is an elevational view of the right-hand side of the electric conductor bar and guard support shown in FIG. 1.

FIG. 5 is a sectional view on the line 5—5 of FIG. 2.

FIG. 6 is a top plan view of an alternative embodiment of the electric conductor bar and guard support.

FIG. 7 is a side elevational view of the electric conductor bar and guard support shown in FIG. 6, the opposite side being a mirror image thereof.

FIG. 8 is an elevational view of the left-hand side of the electric conductor bar and guard support shown in FIG. 6.

FIG. 9 is an elevational view of the right-hand side of the electric conductor bar and guard support shown in FIG. 6.

FIG. 10 is a sectional view on the line 10—10 of FIG. 6.

The fragmentary broken line showing of the guard in FIGS. 1, 2, 6 and 7, as well as the sectional broken line showing of the bar in FIGS. 2 and 7, is for illustrative purposes only.

I claim:

The ornamental design for an electric conductor bar and guard support, as shown and described.
